UNITED STATES PATENT OFFICE.

BEVERLY A. LUNDY, OF ALBANY, NEW YORK, ASSIGNOR TO HALL SWITCH & SIGNAL CO., A CORPORATION OF MAINE.

ADJUSTABLE RESISTANCE UNIT.

1,276,384.

Specification of Letters Patent. Patented Aug. 20, 1918.

Application filed January 29, 1918. Serial No. 214,368.

To all whom it may concern:

Be it known that I, BEVERLY A. LUNDY, a subject of the King of Great Britain, and a resident of Erie street, Albany, New York, 5 have invented Improvements in Adjustable Resistance Units, of which the following is a specification.

My invention relates to an improved form of adjustable resistance to be used in electric 10 circuits to vary the resistance of the same.

One object is to provide a resistance unit whereby the resistance of a circuit may be changed without interrupting the flow of current in the circuit.

15 Another object is to provide a resistance unit which is non-inductive and adjustable.

A further object is to provide a unit which may be easily adjusted with the maximum fineness of adjustment.

20 A further object is to provide a unit which has a fixed non-adjustable resistance and an adjustable resistance so that the resistance may not be reduced below a certain point.

Still further objects and advantages of 25 the invention will be apparent from the accompanying description and the appended claims.

Figure 1 shows a plan of the unit complete.

30 Fig. 2 is a longitudinal section through the unit showing the electrical connections, the means of clamping the unit to its base and also the means of adjustment of the same.

35 Fig. 3 shows the resistance coil independent of the unit in order to show the form of the non-inductive winding.

Fig. 4 is a plan view of Fig. 3.

40 Fig. 5 is the plan of a modified form of adjusting collar.

Referring to Figs. 1 and 2 I have shown at 1 a base which may be made of any suitable insulating material. The base 1 is provided with a recess 2 on the under side 45 thereof and an opening 3 which passes through the base and terminates in a raised boss, 4. The base is further supplied with screw holes 5 and 6 and is adapted to carry at either end binding posts 7 and 8 for the 50 purpose of connecting the resistance unit into any electrical circuit. An upright member 9 of suitable insulating material is provided with an enlarged lower part 10 and a suitable spacing thread 11 around its 55 outer circumference. A wire 12 of suitable

resistance material is provided which passes from binding post 7 through the enlarged part 10 and is wound in such a way as to lay in the threads 11 formed on the upright member 9, passing around this member in 60 the thread to the top of the member, passing across the member 9 at the top in a slot 13 provided therefor and passing around a parallel thread to the bottom of the member and connecting to the terminal 8. 65

By referring to Figs. 3 and 4 it will be seen that the wire 12 will lay in parallel concentric windings passing from the terminal 7 around windings to the top of the member 9 and thence back around parallel windings to the terminal 8, the parallel windings thereby serving to counteract their respective self inductions, thereby making the resistance non-inductive. The upright member 9 with its windings 12 is passed 75 through the opening 3 in the base 1. A clamping nut 14 made of suitable insulating material is provided with a thread 15 adapted to engage the outer periphery of the windings 12 in such a manner that when the clamping nut 14 is screwed down over the windings 12, it will clamp the upright member 9 with its winding, in the position shown. The member 14 will also serve to seal a portion of the winding 12 in the 80 opening 3 of the base 1. The split nut 16 made of suitable conducting material is also provided with the thread 17 adapted to engage the winding 12, this nut being split at 85 18 in order that it may spring together to 90 tightly clamp about the wire 12. From the above it will be seen that normally a circuit will pass from binding post 7 through wire 12 up one spiral of the winding on member 9 and down the other spiral of the winding to binding post 8. However, when nut 95 16 is threaded over the winding 12, it will serve to short circuit a corresponding number of turns in accordance with the distance which it is threaded down over the winding 100 and it will be apparent that by rotating the nut 16 thereby screwing it up and down over the surface of winding 12, that more or less turns of the winding will be shunted out by the nut thereby varying the total 105 resistance of the circuit between binding posts 7 and 8.

Referring to Fig. 5 I have shown a modified form of split nut which is cut away at 19 leaving small contact surfaces at 20 110

which are provided with threads 21. It will be seen that with this form of nut a greater contact pressure may be obtained per unit of area on the outside periphery of wire 12 than with a solid nut.

While I have shown and described one specific form and mode of construction of my device, it is obvious that various forms of construction may be used without departing from the spirit of the invention.

What I claim is:—

1. A resistance unit comprising a base of insulating material, a threaded upright member adapted to pass through said base and be supported by same, resistance wire wound coincident with the threads on said threaded member, a cavity formed in the base for inclosing a portion of said resistance wire, a collar of insulating material threaded over said resistance wire to lock the upright member in place and seal the inclosed portion of said resistance wire, and a collar threaded over said resistance wire and adapted to make electrical contact with the resistance winding and adapted to be rotated about the winding to adjust the resistance of the same.

2. In a resistance unit, a non-inductive helical resistance winding, and a collar of conductive material threaded over said helical winding and adapted to shunt turns of said winding to adjust the resistance of the same.

3. In a resistance unit, a helical resistance winding, and a collar threaded over said helical winding and adapted to make electrical contact with more than one turn of same, and means for rotating said collar about the winding to adjust the resistance of the same.

4. In a resistance unit, a non-inductive helical resistance winding, a collar threaded over said helical winding and adapted to make electrical contact with more than one turn of same, and means for rotating said collar about the winding to adjust the resistance of the same.

5. In a resistance unit, a helical resistance winding, a portion of said winding being of non-adjustable fixed resistance, and a collar of conductive material threaded over said helical winding and adapted to shunt turns of said winding to adjust the resistance of the same.

6. In a resistance unit, a non-inductive helical resistance winding, a portion of said winding being of non-adjustable fixed resistance, and a collar of conductive material threaded over said helical winding and adapted to shunt turns of said winding to adjust the resistance of the same.

7. In a resistance unit, a helical resistance winding, a portion of said winding being of non-adjustable fixed resistance, a collar threaded over said helical winding adapted to make electrical contact with more than one turn of same, and means for rotating said collar about the winding to adjust the resistance of the same.

8. In a resistance unit, a non-inductive helical resistance winding, a portion of said winding being of non-adjustable fixed resistance, a collar threaded over said helical winding and adapted to make electrical contact with more than one turn of same, and means for rotating said collar about the winding to adjust the resistance of the same.

9. A resistance unit comprising a base of insulating material, a threaded upright member of insulating material removably mounted in said base, a resistance wire wound coincident with the threads on said threaded member, and a collar of conductive material threaded over said resistance wire and adapted to shunt turns of said resistance wire to adjust the resistance of the same.

10. A resistance unit comprising a base of insulating material, a double pitch threaded upright member of insulating material supported by said base, resistance wire wound coincident with the threads on said threaded member, and a collar of conductive material threaded over said resistance wire and adapted to shunt turns of said resistance wire to adjust the resistance of the same.

11. A resistance unit comprising a base of insulating material, a threaded upright member of insulating material supported by said base, a resistance wire wound coincident with the threads on said threaded member, means for permanently inclosing a fixed portion of said resistance wire, a collar threaded over said resistance wire and adapted to make electrical contact with more than one turn of same, and means for rotating said collar about the winding to adjust the resistance of the same.

12. A resistance unit comprising a base of insulating material, a double pitch threaded upright member of insulating material supported by said base, resistance wire wound coincident with the threads on said threaded member, means for inclosing a portion of said resistance wire, a collar threaded over said resistance wire and adapted to make electrical contact with more than one turn of same, and means for rotating said collar about the winding to adjust the resistance of the same.

In testimony whereof, I have signed my name to this specification.

BEVERLY A. LUNDY.
